United States Patent Office

Des. 210,915
Patented Apr. 30, 1968

210,915

PROJECTION READER

Kenneth W. Scott, Rochester, N.Y., assignor to Eastman Kodak Company, Rochester, N.Y., a corporation of New Jersey

Filed Jan. 30, 1967, Ser. No. 5,597

Term of patent 14 years

(Cl. D61—1)

FIG. 1

FIG.2

FIG.3

FIG.4

FIG. 5

FIG. 6

FIG. 7

FIGURE 1 is a front perspective view of a projection reader showing my new design;

FIGURE 2 is a left side elevational view thereof;

FIGURE 3 is a right side elevational view thereof;

FIGURE 4 is a rear elevational view thereof;

FIGURE 5 is a top plan view thereof;

FIGURE 6 is a bottom plan view thereof; and

FIGURE 7 is a front elevational view thereof.

I claim:

The ornamental design for a projection reader, as shown.
